(57) **CLAIM**

The ornamental design for an adaptor for lamp connector, as shown and described.

DESCRIPTION

FIG. 1 is a top, front and right side of an adaptor for lamp connector showing my new design, in use condition;

FIG. 2 is a top, rear and left side perspective view thereof;

FIG. 3 is a front elevation view thereof;

FIG. 4 is a right side elevation view thereof;

FIG. 5 is a left side elevation view thereof;

FIG. 6 is a back side elevation view thereof;

FIG. 7 is a top plan view thereof;

FIG. 8 is a bottom plan view thereof; and,

FIG. 9 is a top, rear and left side perspective view thereof, not in use condition.

The broken line of the environment is included to show unclaimed subject matter only and forms no part of the claimed design.
